FLUID CONTROL MEANS

Peter Eduard Geldhof and Luther Ringer, St. Joseph, Mich., assignors to Whirlpool Corporation, a corporation of New York

Application February 8, 1947, Serial No. 727,390

8 Claims. (Cl. 137—565)

1

The present invention relates to improvements in home laundry apparatus. More particularly, the present invention is concerned with a novel fluid control system and means adapted to be used in an automatic washing, rinsing and drying machine having associated therewith suitable storage facilities for the temporary storing of the cleansing solution pending the completion of additional operating steps in the cycle of operation of the machine.

The present invention is particularly advantageously adapted for use in connection with laundering apparatus in which the articles to be laundered are first washed in a hot soapy solution and then rinsed and dried by the same machine. After each washing operation it is highly desirable to save the hot soapy solution for use in the washing of additional batches of clothes since many times either sufficient hot water or large quantities of soap is not available. It is therefore advantageous to remove the soapy solution to a suitable storage member, such as a standard laundry tub, pending the completion of the several rinsing and drying steps of the cycle.

It is customary in laundry apparatus employed for removing the cleansing solution to a storage chamber for subsequent reuse, to provide a pump for removing the solution from the tub of the washing machine and a two way valve with suitable discharge conduits for directing the liquid removed from the tub either to storage or to drain. A second pump and connector piping must be used to return the liquid from the storage chamber to the tub.

In the present invention a single pump unit comprising a pump and a plurality of valves disposed immediately adjacent the pump in the inlet and outlet connections to the pump are so arranged as to permit liquid to be moved from the tub to storage, from storage to the tub or from the tub to drain without reversing the direction of the pump. Since the space available in a washing machine for mechanical apparatus is necessarily small, the importance in this field of a single unit which will efficiently perform the operations heretofore accomplished by use of several units is manifest.

While the apparatus of the present invention is capable of employment in a wide variety of fluid handling operations, it is particularly well adapted to use with an automatic washing, rinsing and drying machine and will, therefore, for the sake of clarity but in no sense of limitation, be described in its adaptation to such equipment. As

2

is customary in the use of such equipment, a complete cycle of operation is performed on a single batch of articles to be laundered including washing, rinsing and drying steps before any subsequent batches of laundry are introduced to the apparatus. The rinsing operations, of which there are ordinarily several, usually employ only clear water of relatively low or medium temperature and, therefore, may be discharged to the drain in order that a fresh water supply may be employed for each of the operations.

In the case of the washing step, however, an abundance of water of relatively high temperature having large quantities of soap and other suitable cleansing agents therein is required. In the interest of saving both hot water and soap, it is, therefore, particularly advantageous to remove the soapy water from the container of the automatic washing, rinsing and drying machine following the washing step and temporarily storing it until the remaining steps of the cycle of operation, all of which are performed in or with the aid of the container of the machine, are completed. The soapy water employed in the first washing step may again be introduced to the container for reuse upon the completion of the remaining steps of the laundering operation.

Such a procedure as herein outlined makes possible a considerable saving in the hot water supply and also in the quantity of detergents required to complete the laundering operation.

It is, therefore, an object of the present invention to provide means capable of producing the aforementioned advantageous results and in so doing, to facilitate the use of the automatic washing, rinsing and drying apparatus.

It is a further object of the present invention to provide a suitable fluid control means which is capable of being connected for operation by the automatic control mechanism for operation in conjunction with the apparatus employing the fluid for the various phases of the laundering cycle.

It is a still further object of this invention to provide a novel pump and valve unit capable of selectively discharging the liquid in the tub either to a storage chamber, to a drain or of returning liquid from the storage chamber to the tub.

It is another object of the present invention to provide a novel tub and valve unit that is simple in construction and compact in arrangement for convenient mounting in the casing of a typical household washing machine.

Other objects and novel features of the present

invention will be apparent from the following detailed description of one embodiment of the present invention as illustrated in the accompanying drawings.

On the drawings:

Figure 1 is a fragmentary vertical sectional view of the automatic washing, rinsing and drying machine with which the device of the present invention is particularly advantageously adapted to be employed;

Figure 2 is a horizontal sectional view taken substantially on line II—II of Figure 1;

Figure 3 is a vertical sectional view, partly broken away, of the valve unit of this invention taken on line III—III of Figure 2;

Figure 4 is a horizontal sectional view of the valve unit of the present invention taken substantially on line IV—IV of Figure 3;

Figure 5 is a side elevational view of the valve unit of the present invention;

Figure 6 is a chart illustrating the complete operating cycle for an automatic washing machine indicating the association of the various operations performed by the machine;

Figure 7 is a diagrammatic showing of a typical electrical circuit for controlling the operation of an automatic washing machine embodying the pump and valve unit of the present invention;

Figure 8 is an enlarged view of the several cam disks for the timer mechanism in disassembled relation in their respective angular positions relative to each other; and

Figure 9 is a diagrammatic showing of a washing machine with which the fluid control system of this invention may be advantageously employed and also illustrating a convenient type of storage and drain means.

As shown in the drawings:

The reference numeral 10 in Figures 1 and 2 is a typical automatic washing, rinsing and drying machine of the kind with which the means of the present invention may be advantageously employed. A casing 11 is provided in which is mounted the operating elements of the apparatus including a tub 12, a drive mechanism 13 including a motor 14 adapted to actuate an agitator (not shown) in the tub and an extractor (not shown). It is to be understood that the casing 11 is enclosed on all sides and at the top and has a suitable access door for introducing the articles to be laundered.

The pump and valve unit of this invention includes the pump 15 which is suitably driven by the motor 14 through a pulley mechanism 16 and has intake and discharge connections 17 and 18, respectively. The intake connection 17 takes suction from a conduit 21 (Figure 3) of a valve unit assembly 20 of interconnected conduits and valves, being secured to the member 21 by a suitable connector 22. As best seen in Figures 3 and 4, the conduit 21 is secured into the assembly 20 at a low level passing directly underneath a pair of upwardly extending riser conduits 23 and 24, the passageway afforded by the conduit 21 being in communication with the vertical passages of the conduits 23 and 24. The end wall of the conduit 21 is blended upwardly into the vertical conduit 24. Thus the conduit 21 which is connected to the suction part of the pump 15 is disposed to draw liquid only from the conduits 23 and 24.

The outlet connection 18 of the pump 15 is secured to a conduit 25 by a suitable connector 26. The conduit 25 is also arranged in the assembly 20 at a low level, passing directly underneath upwardly extending riser conduits 27, 28 and 29,

the passageway afforded by the conduit 25 being in communication with the vertical passages afforded by the conduits 27, 28 and 29. The end wall of the passageway of conduit 25 is blended upwardly into the lower part of the vertical conduit 29. Thus conduit 25, which is connected to the discharge side of the pump 15, is disposed to deliver fluid into any of the vertical conduits 27, 28 and 29.

Referring to Figures 3 and 4, it is seen that each of the vertical riser conduits 23, 24, 27, 28 and 29 is surrounded by a cylindrical wall which is disposed in spaced relation therewith, forming an annular passageway between said cylindrical wall and the conduits. Each riser conduit extends upwardly to a point somewhat below the upper end of the cylindrical wall associated therewith. Thus, liquid flowing upwardly in a vertical conduit may flow through the opening at the upper end thereof and over the upper edges of the conduit into the annular passageway provided between the conduit and the wall.

In general, each vertical conduit is segregated from all others by the cylindrical wall therearound. However, there is provided a cross connection 30 between the annular passageways around the conduits 23 and 27 and a second cross connection 31 between the annular passages around the riser conduits 24 and 28. It is to be noted that these cross connections are at a level higher than that in which the conduits 21 and 25 are connected into the assembly 20.

Communication between the unit 20 and the tub 12 of the washing machine is provided by a conduit 32 which is connected at the same high level as cross connection 30 into the annular passage around the vertical conduit 27. The free end of the conduit 32 is adapted to be secured (Figures 2 and 3) by a suitable connector 33 to a conduit 34 leading from the sump 35 of the tub 12.

Means for directing liquid from the assembly 20 into a storage chamber is provided by a conduit 40 leading from the annular space around the vertical conduit 24 at the high level. Conduit 40 may be conveniently secured to a pipe 41 which is suitably connected into an opening in a priming tank 42. A pipe member 43 leads from the upper side of the priming tank and is adapted to be attached to any suitable conduit 44 which may conveniently be brought upwardly between the tub 12 and the casing 11, through an opening in the upper portion of the casing for discharge into a storage chamber, such as a standard laundry tub which has its drain connection closed, as illustrated in Figure 9.

The discharge to a drain is provided in the form of a conduit 45 which is connected into the annular space around the vertical conduit 29. This conduit 45, which is also disposed at the high level, may be secured, as by a connector 46, to a discharge tube 47 leading from the casing to a drain connection.

For the purpose of controlling the flow of liquid through the vertical conduits 23, 24, 27, 28 and 29, there is provided a flexible valve member 50 which is adapted to be positioned by spring action across the opening at the top of each vertical conduit, as illustrated in Figure 3. The valve member 50 is positioned on the assembly 20 by means of an inverted cup-shaped casing 51 which is fastened onto the assembly 20 by means of cap screws 51a, which also pass through the outer marginal edges of the valve

50 disposed between the assembly 20 and the casing 51.

Each vertical conduit is normally closed by the valve 50 due to the action of a coiled spring 55 on the valve. As a means of lifting the valve off its seat to permit flow of liquid through the conduit, there is provided in each cup-shaped casing 51, a solenoid 52 supported by a retaining member 53 which is held in position by a snap ring 54, adapted to lock into a circular groove in the cup-shaped casing 51. Electrical power connections to the solenoid may be conveniently led into the cup-shaped casing 51 through passages 56 and 57 provided in the top surface thereof.

An armature 58, disposed in the solenoid 52, is suitably secured at its lower end to the valve 50. The upper end of the armature 58 is arranged to abut, as a limiting upward position, a stop 59 depending from the casing 51 by means of a cap screw 60. When the solenoid 52 is energized, the armature 58 will be pulled upwardly against the action of the coiled spring 55 which is disposed around the armature 58 between the valve member 50 and the retaining member 53 and which normally urges the valve against its seat.

As previously stated, the pump and valve unit of this invention is arranged to either move liquid from the tub to storage, from storage to the tub or from the tub to drain. This is accomplished by opening certain valves while allowing the others to remain closed. For convenience the solenoid units of the various valve members will be indicated in Figure 2 as 1-M, 2-M, 3-M, 4-M and 5-M.

Flow of liquid from the tub to storage is effected by opening the valves of the units 2-M and 3-M and then operating the pump. Under these conditions, liquid coming from the tub 12 through the sump 35 and the conduit 34 will enter, at the upper level, the annular space surrounding the vertical conduit 27. Since the valve 50 of the unit 1-M is closed, the liquid will flow across the connecting passage 30 to the annular space surrounding the vertical conduit 23. It will then be permitted to flow downwardly in the vertical conduit 23 to the member 21 due to the fact that valve of the unit 2-M is off its seat. The liquid in the conduit 21 cannot flow toward the vertical conduit 24 since this conduit is closed by its valve and therefore the liquid must flow through the connection 17 to the suction side of the pump 15. Upon being discharged from the pump 15 into the outlet connection 18, the liquid will pass in the conduit 25 and under the closed vertical conduit 27 and then upwardly through the vertical conduit 28, the valve member of which has been lifted off its seat. When the liquid reaches the upper level it will be directed through the cross connection 31 to the annular space around the conduit 24. Since the valve of unit 4-M is closed, the liquid will pass out through the conduits 40 and 41, the priming tank 42 and the pipe 43 to the storage chamber.

To effect the flow of liquid from the storage tank to the tubs the valves of the units 4-M and 1-M are opened and the pump is operated. It is to be noted that the priming tank 42 has sufficient capacity to prime the pump 15, which may suitably be a centrifugal pump. With the valve of unit 4-M open, the liquid entering the annular space about the conduit 24 from the priming tank 42 will flow downwardly in the ver-

tical conduit 24 into the tubular member 21 where it will be directed to the suction side of the pump 15. Upon being discharged from the pump 15 into the outlet connection 18, the liquid will pass into the conduit 25 and upwardly in the vertical conduit 27. Since the valve of the unit 1-M is open, the liquid will flow into the conduit 34 and then upwardly into the tub 12 through the sump 35.

Flow of liquid from the tub 12 to the drain is accomplished by operating the pump 15 when the valves of the unit 2-M and 5-M are open. With these valves open, the liquid coming from the tub 12 through the sump 35 in the conduit 34 will enter at the upper level of the annular space around the vertical conduit 27. Since the valve 50 of the unit 1-M is closed, the liquid will flow across the connecting passageway 30 to the annular space around the vertical conduit 23. It will then be permitted to flow downwardly in the vertical conduit 23 to the conduit 21 due to the fact that the valve of unit 2-M is off its seat. In the conduit 21 the liquid will be directed to the suction side of the pump 15 through the inlet connection 17. Upon being discharged from the pump 15 into the outlet connection 18, the liquid will pass into the conduit 25, under the closed vertical conduits 27 and 28 and up through the vertical conduit 29, the valve member of which has been lifted off its seat, to the upper level where it is directed to drain through the discharge connection 47.

From the foregoing description it is evident that the pump and valve assembly of this invention is capable of directing liquid to the storage, to the drain or back to the pump as desired by selectively closing a combination of valves.

It is of course evident that the pump and valve unit of this invention, the valves of which are solenoid operated and the pump of which is operated through an electric motor, will readily lend itself to operation by an automatic timing device which will control the various operations of the washing, rinsing and drying cycle in which the cleansing solution and the rinse water are used.

The electrical control circuit for the operation of the automatic washing machine with which the pump and valve unit of the present invention is advantageously adapted to be employed may include any suitable form of timing device for controlling the sequential performance of the series of steps in a complete laundering operation. A conventional form of timer 65, which has been diagrammatically illustrated in Figure 7 of the accompanying drawings, employs a shaft 66 attached to a control disk 67 which may conveniently be mounted on the upper portion of the casing 11 of the machine for operation by the operator. A motor 68 is also provided for rotating the shaft and a plurality of cam disks 69 to 76 inclusive. The details of the cam disks 69 to 76 inclusive which are mounted on the shaft 66 and rotated therewith will best be understood from reference to Figure 8 of the drawings. The power supply conductors 77 and 78 provide electrical energy for the timer 65 and the main motor 14.

The cam disk 74 controls that part of the mixer valve 80 which delivers hot water while the cam disk 72 controls the delivery of the mixed water supply from another part of the mixer valve 80 to the tub 12 of the automatic washing machine at the proper intervals. The temperature of the water delivered depends upon the setting by the

operator of the control knob 81 mounted in the upper portion of the casing 11. The adjustment of the knob 81 mounted on the shaft 82 of the temperature control unit causes the cam disks 83 and 84 to be rotated to a position such that the associated movable contacts 85 and 86, respectively, are caused to make or break contact with certain contacts 87 and 88, respectively, for the mixer valve 80.

It will be understood that when the movable contact 85 is permitted, by the position of the cam disk 83 associated therewith, to contact the fixed contact 87, the valve 80 will deliver hot water when it is opened at the proper intervals by the cam disk 74 of the timer 65. In the same way, when the movable contact 86 is permitted by the cam disk 84 to contact the fixed contact 88, the valve 80 will deliver mixed water as it is opened by the cam disk 72 of the timer 65. Thus, with the control knob 81 in the position illustrated in the diagrammatic illustration of Figure 7, both hot and mixed water will be introduced simultaneously by the mixer valve 80 to the tub 12 of the washing machine as the cam disks 74 and 72 of the timer unit 65 operate the mixer valve 80 at the proper intervals.

It is to be noted that another cam 76 also is adapted to close the circuit to the mixed water side of the mixer valve 80. This cam 76 is used to introduce mixed water during the rinse period.

The cam 69 is adapted to close circuits to the solenoids of the valve lifting units 3-M and 5-M. The cam 70 controls the operation of a shifter mechanism E which causes the motor 14 to actuate the extractor unit (not shown). The cam 71 is employed to periodically close the circuit which energizes the motor 14. Cam 73 controls the solenoid of the valve lifting unit 2-M. The cam 74, besides controlling the operation of the hot water side of the mixer valve 80, also is adapted to close the circuit which controls the solenoid of the valve lifting units 1-M and 4-M. The cam 75 is employed to periodically energize the electrical circuit which permits the motor 14 to actuate the agitator shifter mechanism A.

The cams 69 to 76 inclusive are provided with movable contact arms 90 to 97 inclusive respectively. The contact arm 90 associated with the cam disk 69 is provided with a follower 100 which is adapted to trace the periphery of the cam disk 50 and in so doing causes the contact arm 90 to move between the fixed contacts 101 and 102 intermittently making and breaking contact therewith. Likewise the contact arm 95 associated with the cam disk 74 is provided with a follower 103 which traces the periphery of the cam disk to make and break contact with the pair of fixed contacts 104 and 105. The movable contact arms 91, 92, 93, 94, 96 and 97 which are associated respectively with the cam disks 70, 71, 72, 73, 75 and 76 60 are equipped with followers 106, 107, 108, 109, 110 and 111, respectively, which as in the previous case trace the periphery of the cam disks to make and break contact with single fixed contacts 112, 113, 114, 115, 116 and 117, respectively.

The timer unit 65 is provided with a switch embodying a disk 120 and contacts 121 and 122 which enable the operator, by grasping the control knob 67 and moving the shaft 66 slightly in an axial direction, to reset the timer at certain desired positions in the cycle of operation and thereby adjust the comparative length of certain of the operating steps. A suitable fluid level control device, indicated generally by the reference character 125, may be associated with the 75

tub 12 of the automatic washing machine. This device aids in controlling the depth of the water in the tub 12 so as to maintain the same at the proper operating level and to prevent the operation of certain of the elements of the washing machine when an insufficient quantity of water is present to properly complete the operation, as well as to indicate when all of the water is removed from the tub that may be desired for the extracting operation, for example.

The fluid level control 125 may take any suitable form, usually employing a pair of floats one of which indicates when the water in the tub 12 has reached the desired upper level and the other of which indicates when all of the water has been removed from the tub. Each of the floats is associated with suitable switch elements such, as for example, mercury or toggle switches 126 and 127.

With the conventional timing mechanism employed in connection with the apparatus of the illustrated embodiment of the present invention, the motor 68 rotates the shaft 66 of the timer 65 in a step-by-step action at approximately 60 second intervals. More specifically, the construction of the timer 65 is such that the shaft 66 is rotated through an angle of approximately 8° every 60 seconds. As the several cam disks 69 to 76, inclusive, mounted upon the shaft 66 are rotated in the direction indicated by the arrows in Figure 8, the cam followers of the associated contact arms cause said contact arms to open and close electrical circuits associated with their respective fixed contacts so as to energize one or more of the elements of the washing machine structure and to cause each, in its turn, to perform its required duty in the complete cycle of operation.

Figure 6 is a chart illustrating the complete operating cycle for the automatic washing machine indicating the intervals at which the various operations of the cycle take place. This chart will be considered in connection with the diagrammatic sketch of Figure 7 and the detailed views of the cam as shown in Figure 8 to clearly point out the sequence of operations and more especially to illustrate how the novel pump and valve unit of this invention is adapted to be used in this automatic cycle.

It will be seen by reference to the schedule in Figure 6 that the actual washing cycle is begun by the introduction of hot water and mixed water. However, for the purpose of disclosing the use of the pump and valve unit of this invention in bringing suds that have been previously placed in a storage chamber back to the tub for reuse, the schedule is illustrated for a condition that obtains after one batch of clothes have been completely laundered and preparation for starting the second batch is begun.

For this condition the operator will select the setting of the control disk 67 which will permit the cam follower 107 of the cam 71 to drop into recess cam surface A, thus permitting the movable contact 92 to close against the fixed contact 113. A circuit will now be completed from the power supply conductor 77, through the conductor 130, the motors 14 and 68 in parallel, the conductor 131, the fixed contact 113, the movable contact 92, the bus bar 132, the conductor 138, switch parts 129, 121 and 122 and the conductor 139 to the other power supply conductor 78. Thus the main motor 14 which drives the pump 15 is actuated, as is also the timer motor 68.

Referring to Figure 8, it is seen that when

the cam shaft is selectively rotated by the operator to position the cam follower 107 of the cam 71 on the recess cam surface A, the cam follower 103 of the cam 74 will be forced up on the raised cam surface B, causing the movable contact 95 to close against the fixed contact 105. A circuit will then be complete from the power supply 17 through the conductor 130, the solenoids of the valve lifting units 1-M and 4-M, the conductor 133, the fixed contact 105, the movable contact 95, the bus bar 134, the conductor 135, the fixed contact 136, the switch 126, the conductor 137, the conductor 138, switch parts 120, 121 and 122, and the conductor 139 to the other power supply conductor 78. The closing of this circuit energizes the solenoids of units 1-M and 4-M causing the valves of these units to be moved off their seats and permit flow of liquid from the storage chamber to the tub 12 as previously explained.

Thus by this initial setting of the control disk 67, the operator causes the pump 15 to be actuated simultaneously with the opening of the valves of the units 1-M and 4-M. The timer motor 68 is also operating and will rotate the cam in this operation for three-minutes, at which time the cam follower 107 of the cam 71 will ride out of the recess A thus breaking the contact of the movable contact 92 with the fixed contact 113, thereby stopping the motor 14 and consequently the pump 15. Meanwhile the cam follower 103 of the cam 74 has dropped off the raised cam surface B, resulting in the contact of the movable contact 95 with the fixed contact 105 being broken and the solenoids of the units 1-M and 4-M being deenergized to permit their associated valves to close.

It is to be noted that when the timer motor moves the follower 107 of cam 71 out of recess A the circuit through the timer motor 68 will be broken. The timer motor will remain out of operation and the washing cycle will not begin until sufficient hot and mixed water is added to the tub to bring the fluid level up to the desired point, which point will be indicated by the upper float valve closing against the contact 147.

As the follower 107 of cam 71 moves out of recess A, the follower 103 of cam 74 drops off cam surface B onto the recessed surface C to begin the admission of hot and mixed water to the tub. When the follower 103 is on the cam surface C the movable contact 95 will close against the fixed contact 104. A circuit will then be closed from the power supply conductor 17 through the conductor 130, connections 141 and 142 for the portion of the mixer valve 80 which delivers hot water, the fixed contact 87, the movable contact 85, the conductor 143, the fixed contact 104, the movable contact 95, the bus bar 134, the conductor 135, the fixed contact 136, the switch 126, the conductor 137, the conductor 138, switch parts 120, 121 and 122, and the conductor 139, to the other supply conductor 78.

Contemporaneously, the cam follower 108 of the cam 72 will drop into the recess cam surface D, permitting the movable contact 93 to close on the fixed contact 114, closing a circuit from the power supply conductor 77 through the conductor 130, the connections 144 and 145 for that portion of the mixer valve 80 that delivers mixed water, the fixed contact 88, the movable contact 86, the conductor 146, the fixed contact 114, the movable contact 93, the conductor 135, the fixed contact 136, the switch 126, the conductor 137, the conductor 138, switch parts 120, 121 and 122, 75 which of course is connected to the pump 15, is

and the conductor 139 to the other power supply conductor 78. By virtue of the setting of the temperature control knob 81 illustrated in Figure 7, the movable contact 86 makes contact with its fixed contact 88 so that mixed water will be admitted by the mixer valve 80 simultaneously with the introduction of hot water therefrom to produce a supply of water of medium temperature in the tub 12.

It will be understood that the circuit described above will be complete only as long as the toggle switch 126 of the fluid level control device 125 is in the position illustrated in Figure 7. Thus water will be introduced into the tub 12 on top of the soapy solution previously transferred back to the tub, until the top float actuates this toggle switch 126 which occurs when the desired amount of liquid is in the tub. The circuit which is closed through the fixed contact 136 of the level control 125 will then be broken and the introduction of water will stop. Upon upward movement of the toggle switch 126, it will close against the fixed contact 147 completing the circuit for the timer motor and the main motor 14 thereby causing the agitator drive to be engaged.

Referring to Figure 8 it will be seen that contemporaneously with the cam follower 108 of the cam 72 dropping into the recess cam surface D and the cam follower 103 of the cam 74 dropping into the recess surface C of cam 74, the cam follower 109 of the cam 75 will also drop onto the recess cam surface E thus permitting the movable contact 96 to close on the fixed contact 116. An electrical circuit will then be complete from the power supply conductor 17 and through the conductor 130, the connections 148 and 149 for the agitator shifter mechanism A, the fixed contact 118, the movable contact 96, the conductor 150, the fixed contact 151 on the lower float of the control device 125, which has of course been pivoted upwardly due to the water level of the tub rising, the switch 127, the conductor 152, the fixed contact 147, the switch 126, the conductor 137, the conductor 138, switch parts 120, 121 and 122 and the conductor 139 to the other power supply conductor 78. It will be noted that while this circuit was partially complete when the lower float had closed against the contact 151 of the level control device 125, the agitator mechanism was not energized to close the agitator device until the upper float was closed against the contact 147.

When the upper float closes against the fixed contact 147, a circuit is complete for both the main motor 14 and the timer motor 68 in parallel from the power supply conductor 17 through the conductor 130, the motors in parallel, the conductors 131, 153 and 152, the fixed contact 147, the switch 126, the conductor 137, the conductor 138, switch parts 120, 121 and 122, and the conductor 139 to the other power supply conductor 78.

Thus with the proper amount of washing solution in the tub and the agitator operating, the clothes in the tub will be subjected to a washing operation for the number of minutes that has been selected by the operator for this washing cycle, as for example 20 minutes as indicated in Figure 6.

When the washing cycle is complete the timer motor 68 will rotate the cams into that part of the cycle where the suds is again transferred back to storage for possible reuse. According to the schedule of Figure 6, the main motor 14, 70 which of course is connected to the pump 15, is

again energized by the cam follower 107 of the cam 71 dropping onto the recessed cam surface F causing the movable contact 92 to close against the fixed contact 113 thus closing the circuit through the main motor 14 and the timer motor 68 in parallel through the bus bar 132 and the switch 120 to the power supply conductor 78. Contemporaneously the extractor shifting mechanism E and the solenoids of the valve lifting units 2-M and 3-M are energized to operate their associated units. It will be understood that the suds will first be transferred to the storage tank before the extractor unit is actuated and then, when the lower float control of the fluid level device 125 drops onto the contact 155, the extractor unit will be energized and the soapy solution so extracted will also be moved to the storage chamber.

The electrical circuit for the operation of the solenoid of the unit 2-M is completed from the power supply conductor 77 when the cam follower 109 of the cam 73 drops onto the recess cam surface H causing the movable contact 94 to close on the fixed contact 115. The circuit is then complete from the power supply conductor 77 through the conductor 130, the solenoid of the unit 2-M, the conductor 156, the fixed contact 115, the movable contact 94, the bus bar 132, the conductor 138, switch parts 120, 121 and 122, and the conductor 139 to the other power supply conductor 78.

The electrical circuit for the operation of the solenoid of the unit 3-M is completed when the cam follower 100 of the cam 69 rides up on the raised cam surface I causing the movable contact 90 to close on the fixed contact 102. The circuit is established from the power supply conductor 77 through the conductor 130, the solenoid of the valve lifting unit 3-M, the conductor 157, the fixed contact 102, the removable contact 90, the conductor 138, switch parts 120, 121 and 122 and the conductor 139 to the other power supply conductor 78. As previously described, when the valve of the units 2-M and 3-M are moved off their seat, the pump and valve unit of this invention is disposed to direct liquid from the tub of the washing machine to the storage chamber. Thus in this cycle with the pump operating and these valves open the suds will be returned to the storage chamber. When the lower float of the fluid level control 125 drops as the water is extracted from the tub and moves it on the fixed contact 155, the electrical circuit for the operation of the shifting mechanism E of the extractor, which may conveniently be of the rotating basket type, will be closed since the cam follower 106 of the cam 70 drops onto the recess cam surface G contemporaneously with the closing of the circuit through the solenoid of the units 2-M and 3-M. The circuit through the extractor shifting mechanism E is complete from the power supply conductor 77 through the conductor 130, the connections 153 and 154 of the shifter mechanism E, the fixed contact 112, the movable contact 91, the conductor 158, the fixed contact 155, the switch 127, the conductor 153, the fixed contact 113, the movable contact 92, the bus bar 132, the conductor 138, the switch parts 120, 121 and 122, and the conductor 139 through the other power supply conductor 78. For the remainder of the cycle the suds extracted by the extractor unit will also be moved to the storage chamber since the valves of the units 2-M and 3-M are open and the pump is operating.

When the extraction cycle is over, the timer control motor 68 will move the cams into the rinse cycle. Referring to Figure 8, it will be observed that the cam follower 111 of the cam 76 drops down onto the recess cam surface J permitting the movable contact 97 to close on the fixed contact 117. Thus there will be closed through that portion of the mixer valve which delivers mixed water to the tub an electrical circuit from the power supply conductor 77, through the conductor 130, the connections 144 and 145, for that portion of the mixer valve 80 that delivers mixed water, the conductor 159, the fixed contact 117, the movable contact 97, the bus bar 134, the conductor 135, the fixed contact 136, the switch 126, the conductor 137, the conductor 138, the switch parts 120, 121 and 122, and the conductor 139 to the other power supply conductor 78.

Contemporaneously with the circuit being closed through the mixer valve, a circuit is also closed through the shifting mechanism A of the agitator mechanism when the cam follower 110 of the cam 75 drops onto the recess cam surface K permitting the movable contact 96 to close on the fixed contact 116. Thus the agitator is ready to be energized when the upper float of the liquid level control device 125 is moved upwardly to close on the fixed contact 147 when the water is at the proper level. When the upper float closes on the contact 147, an electrical circuit will be closed through the motor 14 which drives the agitator. Also, an electrical circuit through the agitator shifting mechanism A will be closed from the power supply conductor 77 through the conductor 130, the connections 148 and 149 of the agitator shifting mechanism, the fixed contact 116, the movable contact 96, the conductor 150, the fixed contact 151, the switch 127, the conductor 152, the fixed contact 147, the switch 126, the conductor 137, the conductor 138, switch parts 120, 121 and 122, and the conductors 139 to the other power supply conductor 78. For the remainder of this cycle the agitator will tumble the clothes around in the rinse water and thus thoroughly rinse them.

When the rinse cycle is completed the timer motor 68 will move the cams into the rinse water extraction cycle in which the rinse water is directed from the tub to a drain connection. As previously explained this will be accomplished when the valves of the valve lifting units 2-M and 5-M are moved off their seats.

To close the circuit through the motor 14 the cam follower 107 of cam 71 drops onto the recess cam surface L, moving the movable contact 92 onto the fixed contact 113 and closing the circuit from the motor through the bus bar 132 and switch 120 to the power supply conductor 78. The electrical circuit for the operation of the solenoid of the valve lifting unit 5-M is completed when the cam follower 100 of the cam 69 drops onto the recessed cam surface M permitting the movable contact 90 to close on the fixed contact 101. Then the electrical circuit is complete from the power supply conductor 77 through the conductor 130, the solenoid of the valve lifting unit 5-M, the conductor 160, the fixed contact 101, the movable contact 90, the conductor 138, the switch parts 120, 121 and 122, and the conductor 139 to the other power supply conductor 78.

An electrical circuit is closed for the actuating of the valve lifting unit 2-M when the cam follower 109 of the cam 73 drops onto the recess cam

13

surface M permitting the movable contact 94 to close on the fixed contact 115 and establish the circuit from the power supply conductor 11, through the conductor 130, the solenoid of the valve lifting unit 2-M, the conductor 156, the fixed contact 115, the movable contact 94, the bus bar 132, the conductor 138, the switch parts 120, 121 and 122, and the conductor 139 to the other power supply conductor 78.

The extractor shifting mechanism E will be energized when the cam follower 106 of the cam 70 moves onto the recess cam surface P permitting the movable contact 91 to close on the fixed contact 112, thus establishing an electric circuit from the power supply conductor 17 to the conductor 130, the connections 153 and 154 of the shifter mechanism E, the fixed contact 112, the movable contact 91, conductor 158, the fixed contact 155, the switch 127, the conductor 153, the fixed contact 113, the movable contact 92, the bus bar 132, the conductor 138, the switch parts 120, 121 and 122, and the conductor 139 to the other power supply conductor 78. It is to be noted that, as in the suds extracting cycle, the extractor does not operate until the level of the rinse water in the tub allows the lower float to drop.

Thus with the valves of the valve lifting units 2-M and 5-M open and the motor 14 in operation, the rinse water from the tub 12 will be directed to the drain connection. At the end of this cycle of course, the operator can manually move the control disk 67 to the initial position at which the valves of the units 1-M and 4-M are opened and the soapy solution is returned from the storage tank preparatory to beginning a new washing cycle.

From the foregoing description it is seen that there is provided in this invention a novel pump and valve unit which may be advantageously and conveniently attached into an automatic washing, rinsing and drying cycle.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. In a fluid transfer unit selectively operable to transfer fluid through a plurality of paths, a pump, two fluid conduits, one leading to the suction end of said pump and the other leading from the discharge end of said pump, a plurality of cross-connections in a different plane from said two conduits, a plurality of open-ended riser conduits communicating between said conduits and said cross-connections and opening upwardly within said cross-connections and spaced inwardly from the walls thereof, and separate valve means selectively operable to close the open ends of said open-ended riser conduits.

2. In a fluid transfer unit selectively operable to transfer fluid through a plurality of paths, a pump, two fluid conduits, one leading to the suction end of said pump and the other leading from the discharge end of said pump, a plurality of cross-connections spaced above said conduits and extending therealong, a plurality of vertical riser conduits leading from said conduits into said cross-connections within the margins thereof and opening thereinto at their upper ends at levels spaced above the bottoms of said cross-connections, whereby fluid may flow through

14

said open-ended vertical riser conduits into said cross-connections and may flow past the walls of said open-ended vertical riser conduits, and valve means selectively operable to close the open ends of said open-ended vertical riser conduits and affording fluid passageways thereby.

3. A fluid transfer unit for selectively transferring fluid from a predetermined one of three conduits to another comprising a valve unit assembly having a fluid conduit at one level, a pair of conduits at a lower level and having open upper ends communicating at said open ends with said fluid conduit in said valve unit at said one level and spaced inwardly from the wall of said fluid conduit, a separate valve cooperating with the open end of each of said conduits, a second conduit, a second pair of conduits having open upper ends communicating at said open ends with said second conduit and spaced from the wall thereof, a separate valve cooperating with the open end of each of said last named conduits, a pump having intake and discharge ports, one of said conduits of each of said pairs of conduits being connected to said intake port and the other of said conduits of each of said pairs of conduits being connected to said discharge port, a third conduit, an additional conduit having an open upper end communicating at said open end with said third conduit and connected with said discharge port, and a valve cooperating with the open end of said additional conduit.

4. A fluid transfer unit for selectively controlling the flow of a fluid between three conduits comprising a pair of first conduits closed at one end and open at their other ends, a pump having intake and discharge ports connected respectively to said pair of conduits at the open ends thereof, vertical riser conduits extending from said first conduits and having open upper ends, cross-connections spaced from the walls of said vertical riser conduits at the open upper ends thereof and connecting said vertical riser conduits of each pair of conduits together, selectively operable valves cooperating with the open ends of said riser conduits, two conduits connected to said cross-connections and to different ones of said vertical riser conduits, and a third conduit spaced from the margins of said cross-connections and communicating with another of said vertical riser conduits.

5. A fluid transfer unit for selectively controlling the flow of fluid between three conduits comprising a pair of first conduits disposed at a first level and closed at one of their ends and open at their other ends, a pump having intake and discharge ports connected respectively to said first conduits at the open ends thereof, vertical riser conduits leading from said first conduits and having open upper ends, cross-connections between the open upper ends of said vertical riser conduits and spaced outwardly from the margins thereof for cross-connecting said first conduits, three conduits connected to certain of said vertical riser conduits and said cross-connections at a second level, and a separate selectively operable valve cooperating with the open upper end of each of said vertical riser conduits.

6. A fluid transfer unit for selectively controlling the flow of fluid between three conduits comprising a pair of first conduits disposed at a first level and closed at one end and open at their other ends, a pump having intake and discharge ports connected respectively to the open ends of said first conduits, vertical riser con-

duits leading from said first conduits and having open upper ends, cross-connections between said vertical riser conduits at a second level from the level of said first conduits and cross-connecting said first conduits and having walls spaced outwardly from the outer margins of said vertical riser conduits, a selectively operable valve cooperating with the open end of each of said vertical riser conduits and including a separate movable member movable into engagement with the open end of each of said vertical riser conduits and selectively operable to prevent the flow of fluid from the first level to the second through the associated vertical riser conduit, and three conduits connected with certain of said vertical riser conduits in planes beneath said valve member.

7. A fluid transfer unit for selectively transferring fluid from a predetermined one of three conduits to another comprising a pair of first conduits disposed at a first level and closed at one end and open at the other end, a pump having intake and discharge ports connected respectively to the open ends of said first conduits, vertical riser conduits leading from said first conduits and having open upper ends, a separate selectively operable valve cooperating with the open upper ends of each of said vertical riser conduits, cross-connections between said vertical riser conduits connecting said vertical riser conduits at a second level, each of said cross-connections having a substantially cylindrical wall at each end thereof spaced outwardly from the walls of said vertical riser conduits and forming an annular chamber around each vertical riser conduit through which fluid may flow around the associated riser conduit, when said riser conduit is closed by its associated valve, and three conduits connected to different ones of said annular chambers.

8. A fluid transfer unit for selectively transferring fluid from a predetermined one of three conduits to another comprising first and second conduits disposed at a first level, a pump having intake and discharge ports connected respectively to said first and second conduits, vertical riser conduits communicating with and projecting upwardly from said first and second conduits and open at their upper ends, cross-connections between said vertical riser conduits at a second level, each of said cross-connections having a substantially cylindrical wall at each end thereof encircling the open upper end of an associated vertical riser conduit and spaced therefrom and forming annular chambers around the open ends of said vertical riser conduits, a flexible diaphragm member disposed across the top of each cylindrical wall and movable downwardly into engagement with the open end of an associated vertical riser conduit to close the open end of said vertical riser conduit and leave the annular chamber around said vertical riser conduit open for the flow of fluid therearound.
